ABSTRACT OF THE DISCLOSURE

In a clutch of the type including an electrical coil for inducing a magnetic field between the relatively movable clutch structures to operatively interconnect them; one of the structures defines an annular cavity to receive the coil and the coil is wound on a bobbin of electrically insulative material which is then received in the cavity. The bobbin includes a number of spaced bosses which are received in complementary holes provided in the clutch structure and two oppositely positioned ones of the bobbins serve as mountings for the coil terminals. An annular strip of electrically insulative material is provided with a pair of spaced slip rings and includes an equal number of spaced openings with each opening communicating with a different one of the slip rings than the opening disposed opposite it. The strip is mounted on the clutch structure by means of conductive connectors, such as screws, which extend through the openings and holes. Each one of an oppositely disposed pair of the screws engage a slip ring and a terminal. Thus the bobbin and the annular strip are securely mounted on the clutch while the slip rings are electrically connected to the coil.

BACKGROUND OF THE INVENTION

This invention relates to clutches and, more particularly, to electromagnetic clutches. In such devices a rotary input and a rotary output structure are mounted in juxtaposition and a coil is mounted on one of them to induce a magnetic field in them and thus operatively interconnect them. Normally the coil is mounted within the clutch and slip rings must be mounted on an exterior surface of the clutch to electrically connect the coil to a control which is mounted on some stationary portion of the machine involved. Providing secure mechanical connection of the coil and slip rings to the clutch structure while, at the same time, electrically interconnecting these elements has posed substantial problems in the prior art.

An object of this invention is to provide an improved electromagnetic clutch.

Another object is to provide such a clutch having an improved arrangement for mechanically mounting the coil and slip rings and, at the same time, providing electrical connections therebetween.

A further object of this invention is to provide such an improved clutch wherein the mounting and electrical connection is provided with a minimum number of long lasting, low cost parts.

A still further object of this invention is to provide such an improved clutch wherein any possible problem of proper orientation between the coil and slip rings during assembly is eliminated.

SUMMARY OF THE INVENTION

An electromagnetic clutch is provided with a rotary input structure and an adjacent, rotary output structure. One of these structures defines an annular cavity therein to receive an electrical coil for inducing a magnetic field in the input and output structures to operatively interconnect them and defines a plurality of spaced holes therethrough communicating with the cavity. An annular bob-

2

bin or coil support means of insulative material, having an electrical coil wound thereon, is received in the cavity and includes a plurality of spaced bosses which are received in the holes. A pair of the bosses provide mounting for a pair of terminals connected to the ends of the coils. An annular strip of insulating material is provided having a pair of spaced slip rings of conductive material formed thereon. The strip and slip rings define a pair of spaced openings with each one of the openings communicating with a different one of the slip rings. The strip is placed in juxtaposition to the clutch structure with separate conductive securing means engaging one of the slip rings, extending through aligned ones of the holes and openings and engaging one of the terminals so that the bobbin and strip are securely mounted on the clutch structure and the slip rings and coil are electrically connected.

BRIEF DESCRIPTION OF THE DRAWINGS

FIGURE 1 is a side elevational view of a clutch made in accordance with one form of the present invention, the mechanism being shown partially broken away and partially in section to illustrate details;

FIGURE 2 is a perspective view of a portion of the input structure of the clutch of FIGURE 1, the view being partially broken away and partially in section to illustrate details;

FIGURE 3 is a reduced scale plan view of the strip of insulative material used in the clutch of FIGURE 1, illustrating the slip rings and the openings therethrough;

FIGURE 4 is a view taken along line 4—4 of FIGURE 1, illustrating certain details of the clutch mechanism.

DESCRIPTION OF THE PREFERRED EMBODIMENTS

Referring now to the drawing there is shown an electromagnetic clutch 1 including a rotary input structure 2 and an adjacent rotary output structure 3. The input structure is provided with a first or inner, generally radially extending wall 4 which is mounted on the shaft 5 of a suitable motor 6 for rotation therewith by any suitable arrangement such as the key and slot generally illustrated at 7. The outer periphery of the wall 4 joins one edge of an inner, axially extending wall 8. Adjacent its outer edge, the wall 8 joins a second, or outer, radially extending wall 9. The outer periphery of the wall 9 joins an outer axially extending wall 10, which is radially spaced from and parallel to the wall 8, so that the walls 8, 9 and 10 in effect form a recess or cavity in the input structure. The edge of the wall 10 is formed as a clutching surface 11.

The output structure 3 can be connected to drive any suitable mechanism and, for purposes of illustration, it is shown as including an output pulley or hub 12 mounted on the motor shaft 5 by means of a bearing structure 13 so that it can rotate relative to the shaft. The output structure also includes an outer, annular clutching member 14 which is mounted in juxtaposition to the clutching surface 11 of the input structure and is connected to the pulley 12 by an intermediate member 15. The intermediate member 15 is connected to the pulley 12 and the clutching member 14 by any suitable means such as rivets indicated at 16. The clutching member 14 is provided with an annular strip of friction material 17 for engagement with the clutching surface 11.

In order to provide mutual attraction between the input and output structures so that the clutching surface 11 and strip of friction material 17 are brought together with sufficient force to operatively connect these structures, an electrical energizing coil is mounted in the cavity 18 formed by the walls 8, 9 and 10. To this end there is provided an annular coil support means 19 of electrically

insulative material with the coil 20 wound thereon. More particularly, the coil support means includes an annular, axially extending wall 21 joined to a pair of spaced, radially extending walls 22 and 23 to provide a bobbin of U-shaped cross section. The bobbin is open in the radially outward direction, which enables the coil 20 to be wound thereon easily. A covering 20a of suitable material may be wound around the coil and tied to prevent any slippage of the coil. The bobbin is received in the cavity 18 with its axially extending wall 21 mounted closely around the wall 8 of the input structure.

The radial wall 23 is formed with a plurality of hollow bosses 24 as shown in FIGURE 1 and 25 shown in FIGURE 3 which are spaced around the circumference of the wall. These bosses 24 and 25 are received in holes 26 formed in the wall 9 of the input structure so that the wall 23 of the bobbin will fit flush with the inner surface of the wall 9. While the bosses may all be formed to be symmetric in configuration, for ease of manufacturing the bosses 24 are formed to open radially outward while the bosses 25 open tangentially of the edge of the wall 23. In the clutch illustrated there are a pair of bosses 24 on circumferentially opposite sides of the bobbin 19 and each of these bosses receives and mounts a terminal 27 which, in turn, is connected to one end of the coil 20. The terminals 27 include a return bent portion 28, which is mounted within the bosses 24, and an arm portion 29 which extends from the bosses toward the coil for connection to an end of the wire forming the coil. Thus the terminals 27 are firmly mounted in the bobbin and at the same time are electrically insulated from the input structure 4. In the clutch illustrated there also is a pair of bosses 25 which are spaced substantially directly across the bobbin from each other and equally spaced with respect to the bosses 24. The bosses 25 receive generally U-shaped mounting clips 30. The clips 30 are contained substantially completely within the bosses 25 so that they may be used for mechanically securing the bobbin and coil in the clutch while, at the same time, they are electrically isolated and there is no chance that an end of the coil will be connected to them.

When an electrical current is provided to the coil it sets up a magnetic field which flows through both the input and the output structures and causes mutual attraction therebetween. This mutual attraction causes firm engagement between the clutching surface 11 and the friction material 17 so that the input and output structures are operatively connected. To this end there is provided an annular strip of electrically insulative material 31 which has formed thereon a pair of annular, radially spaced, electrically conductive slip rings 32 and 33. Thus the slip rings are electrically isolated from each other. There is formed in the strip 31 two openings 34 which are on circumferentially opposite sides of the strip and one of these openings 34 extends through a portion of the slip ring 32 while the other extends through a portion of the slip ring 33. There are two additional openings 35 formed in the strip 31 directly opposite from each other and displaced 90° with respect to the openings 34. One of the openings 35 also extends through the slip ring 32 while the other extends through the slip ring 33. This forms four openings through the slip rings and strip which are equally spaced circumferentially around the strip with one adjacent pair of the openings extending through or communicating with the slip ring 32 and the other pair extending through or communicating with the slip ring 33. The openings 34 and 35 are radially spaced so that when the strip 31 is positioned against the outside of wall 9 the openings 34 and 35 will be in registry with the holes 26 in the wall 9 and with the bosses 24 and 25.

In order to assure proper lateral placement of the strip with respect to the input structure 4, the wall 8 extends beyond the wall 9 to form a shoulder 8a which fits closely within the radially inner edge of the strip 31, thus fixing the lateral positioning of the strip. All that

then becomes necessary is to rotate the strip until the openings 34 and 35 are aligned with the openings 26 and thus the bosses 24 and 25. Conductive securing means such as screws 36 are inserted through the openings 34 and 35 and holes 26 with the threaded shaft of the screws extending into the bosses 24 and 25 and being threadedly engaged with the terminals 27 or clips 30. The heads of the screws overlie and are in engagement with the slip rings 32 and 33. The alignment of the openings 34 and 35 with respect to the holes 26 and the bosses 24 and 25 is of no significance. As discussed above the terminals 27 are mounted in the directly opposite pair of bosses 25. Also, each of the openings 34 communicate with a different one of the slip rings and each of the openings 35 communicates with a different one of the slip rings. Thus, regardless of the relative positioning of the strip 31 with respect to the wall 9, each end of the coil 20 will be connected to a different one of the slip rings 32 and 33.

Electrical power may be provided to the slip rings 32 and 33 through a pair of electrically conductive brushes or rods 37. The brushes are mounted in a control housing 38 which is illustrated as being positioned on the motor 6 and disposed under the strip 31. The housing 38 contains various control elements forming a control circuit for providing a suitable signal to the slip rings through the brushes. The particular control circuit used forms no part of the present invention and thus a particular circuit has not been illustrated.

From the foregoing it will be seen that there is provided a new and improved electromagnetic clutch with a simplified and yet fool proof arrangement for physically mounting the electrical coil and the slip rings on the clutch and, at the same time, electrically interconnecting the coil and the slip rings with proper isolation of the electrical circuit from other conductive components of the device.

It will be obvious to one skilled in the art that various modifications may be made to the device illustrated without departing from the spirit and scope of the invention. For instance, there could be provided only two bosses, spaced directly across the bobbin from each other, two holes 26 similarly spaced, and two openings in the insulative strip 31, similarly spaced with one connected to each of the slip rings. Where the magnetic clutch is to be relatively large it may be desired, for purposes of the physical mounting of the slip rings and coil to use more than four screws. By using an even number of connecting devices evenly spaced circumferentially around the clutch and by making an adjacent one-half of them extend through one slip ring while the other adjacent one-half of them extend through the other slip ring. In which event there will be provided a corresponding number of openings, holes and bosses, with the terminals mounted in an oppositely disposed pair of the bosses. With such an arrangement the ease of construction with surety of proper coil connection may be maintained. The embodiment illustrated is shown with four screws since, in clutches of the type illustrated that is normally a sufficient number for mechanical attachment purposes, and, therefore, the number four is an optimum.

What we claim as new and desire to secure by Letters Patent of the United States is:

1. An electromagnetic clutch, including:
  - (a) a rotary input structure;
  - (b) an adjacent, rotary output structure;
  - (c) one of said structures defining an annular cavity therein to receive an electrical coil for inducing a magnetic field in said input and output structures to operatively interconnect them;
  - (d) said one of said structures defining a plurality of spaced holes therethrough communicating with said cavity;
  - (e) coil support means of insulative material having an electrical coil mounted thereon, said coil support means being received in said cavity;

- (f) said coil support means including a plurality of spaced bosses received in said holes; a spaced pair of said bosses providing insulated mountings for a pair of terminals connected to the ends of said coil;
- (g) an annular strip of insulating material having a pair of radially spaced, slip rings of conductive material formed thereon, said slip rings and said strip having a pair of spaced openings, each one of said pair of openings communicating with a different one of said slip rings;
- (h) said strip being in juxtaposition to said one of said structures with separate conductive securing means connecting one of said slip rings to one of said terminals and the other of said securing means connecting the other of said slip rings to the other of said terminals, said securing means extending through aligned ones of said holes and openings;
- (i) whereby said coil support means and said strip are mounted on said one of said structures and said slip rings and said coil are electrically connected.

2. The invention as set forth in claim 1, wherein said coil support means is a bobbin of substantially U-shaped cross-section and has its open side disposed in the radially outward direction, whereby said coil may be easily wound on said bobbin.

3. The invention as set forth in claim 1 wherein there are an even number of bosses equally spaced circumferentially around said coil support means with a pair of oppositely disposed ones of said bosses providing the mountings for said terminals; there are an equal number of holes equally spaced circumferentially around said one of said structures; and there are an equal number of openings equally spaced circumferentially around said strip with an adjacent one-half of said openings communicating with one of said slip rings and the other adjacent one-half of said openings communicating with the other of said slip rings; whereby each of said terminals will be connected to a different slip ring than the other of said terminals regardless of the orientation of said strip relative to said coil support means.

4. An electromagnetic clutch, including:

- (a) a rotary input structure;
- (b) an adjacent, rotary output structure;
- (c) one of said structures including an annular, radially extending wall, with an inner and an outer, spaced annular wall extending axially therefrom; said walls defining an annular cavity to receive an electrical coil for inducing a magnetic field in said input and output structures to operatively interconnect them;
- (d) said radially extending wall defining a plurality of spaced holes therethrough communicating with said cavity;
- (e) an annular coil support means of insulative material having an electrical coil mounted thereon, said coil support means being received in said cavity;
- (f) said coil support means including a plurality of spaced bosses received in said holes; a spaced pair of

- said bosses providing insulated mountings for a pair of terminals connected to the ends of said coil;
- (g) an annular strip of insulating material having a pair of radially spaced slip rings of conductive material formed thereon, said slip rings and said strip having a pair of spaced openings, each one of said pair of openings communicating with a different one of said slip rings;
- (h) said strip being in juxtaposition to said radially extending wall with separate conductive securing means connecting one of said slip rings to one of said terminals and the other securing means connecting the other of said slip rings to the other of said terminals, said securing means extending through aligned ones of said holes and openings;
- (i) whereby said coil support means and said strip are mounted on said one of said structures and said slip rings and said coil are electrically connected.

5. The invention as set forth in claim 4 wherein said coil support means includes an annular, axially extending wall joined to a pair of spaced, radially extending walls to provide a bobbin of a generally U-shaped cross-section; said bobbin being received in said cavity with its axially extending wall mounted closely around the inner axially extending wall of said one of said structures; and one of its radially extending walls being formed with said plurality of bosses, which are received in said plurality of holes in said radially extending wall of said one of said structures.

6. The invention as set forth in claim 4 wherein there are an even number of bosses equally spaced circumferentially around said coil support means with a pair of oppositely disposed ones of said bosses providing the mountings for said terminals; there are an equal number of holes equally spaced circumferentially around said radially extending wall of said one of said structures; and there are an equal number of openings equally spaced circumferentially around said strip with an adjacent one-half of said openings communicating with one of said slip rings and the other adjacent one-half of said openings communicating with the other of said slip rings; whereby each of said terminals will be connected to a different slip ring than the other of said terminals regardless of the orientation of said strip relative to said coil support means.
